UNITED STATES PATENT OFFICE.

RICHARD T. MORE, OF DAYTON, OHIO.

BELT-CUTTER.

No. 852,340.

Specification of Letters Patent.

Patented April 30, 1907.

Application filed February 1, 1907. Serial No. 355,297.

To all whom it may concern:

Be it known that I, RICHARD T. MORE, a citizen of the United States, residing at Dayton, in the county of Montgomery and State 5 of Ohio, have invented certain new and useful Improvements in Belt-Cutters, of which the following is a specification.

My invention relates to improvements in cutters for heavy material, and it more particularly relates to a device adapted to the cutting of leather belts.

The object of my invention is to provide a small and inexpensive device of this character for the use of dealers in belts and for 15 use in factories employing belts.

In cutting heavy leather belts by dealers and users, who are of course not equipped with the heavy machinery used by belt manufacturers for this purpose, difficulty 20 has been experienced with the small devices usually employed for this purpose for the reason that it has been hard to maintain the proper relation between the belt and the cutter so as to obtain a straight cut.

25 In the machine which I have devised I have provided means for securely holding the belt and cutter in proper working relation so that the cutting knife can readily be drawn through the length of the belt without 30 any particular care on the part of the operator.

The invention consists in the constructions and combinations of parts hereinafter described and set forth in the claims.

35 In the accompanying drawings, Figure 1 is a plan view of my improved device. Fig. 2 is an end elevation of the same in perspective. Fig. 3 is a perspective view looking from the front showing a belt in position in the device. 40 Fig. 4 is also an end elevation in perspective showing the guide rod in a different position than that shown in Fig. 2. Fig. 5 is a detail of the inner side of one of the gages.

Like parts are represented by similar 45 characters of reference in the several views.

In the said drawings, 1 represents a base rod having a lateral projection, 2, on the forward side thereof in which is secured an inclined cutting knife, 3, through the medium of a 50 clamping plate, 5, and setscrew 4. The rod may also be provided with a series of graduations, as shown in Fig. 1. Located upon this base rod, 1, are two gages, 6 and 7, adapted to be secured in any desired position of adjustment thereon by setscrews, 8 55 and 9; said gages being extended rearwardly

for a suitable distance and provided with handles 10 and 11, as shown.

Extending through the said gages above the base rod is a guide rod, 12; this rod being 60 rounded on one side to conform to the shape of the opening, 13, in each of the gages, and flattened on the opposite side, as shown. Adjusting screws, 14 and 15, are provided in the respective gages to form stops for the 65 rod 12. This construction of the guide rod permits of two adjustments with reference to the base rod, 1, by simply turning the rod so as to permit the rounded portion to rest either in the upper or lower parts of the 70 round openings. In the position shown in Fig. 4 it is adjusted to accommodate a belt of single thickness, while in the position shown in Fig. 2 it is adjusted for a belt 75 of double thickness.

In the operation of the device, the gage 7 will be first adjusted to the position on the base rod determined by the graduations for cutting the width of strip desired. For instance, if it is desired to cut a strip four 80 inches wide, the gage will be set at the 4 inch graduation. The belt, 16, is then slipped in between the respective base and guide rod, the latter rod having been first adjusted to the thickness of the belt, belts 85 being of two thicknesses, a double and single thickness. The other gage 6 is then adjusted on the base rod to a position against the opposite edge of the belt so that the belt will be confined between the two gages; the 90 adjustment of the gages, however, being such as will permit the belt to pass readily between the same without any undue binding or friction. The distance between the two rods is also determined so that the rod 12 95 will act simply as a guide or stop for the belt and will have no binding effect thereon. After the end of the belt has been worked sufficiently past the knife it is secured in some suitable way and the operator, by 100 grasping the handles, can then readily draw the knife through the entire length of the belt. Or, if desired, the cutter itself can be secured and the belt drawn through in a manner which will be readily understood. 105

Inasmuch as the device is especially adapted for cutting belts, which are usually made in two thicknesses only, we have shown the rod 12 capable of two adjustments. It is obvious, however, that the device might be 110 used for other purposes which would require further adjustments of the guide rod.

This could be readily accomplished by making an elongated slot in each of the gages and providing adjustable supporting blocks for the guide rod in a well known manner; these blocks being adapted to be adjusted up and down in the slots by the adjusting screws 14 and 15 in any well known manner.

Having thus described my invention, I claim:

- 10 1. In a cutter for flexible material, a base rod, a cutting knife supported on said base rod, an adjustable gage on said base rod on each side of said knife, and a guide-rod supported in said gages parallel with said base rod, substantially as and for the purpose specified.
- 15 2. In a cutter for flexible material, a base rod, a knife supported thereon, an adjustable gage on each side of said knife, a guide rod supported in said gages parallel with said base rod, and means for adjusting the distance between the respective base and guide rods, substantially as and for the purpose specified.
- 20 3. In a cutter for flexible material, a base

rod, an angularly projecting knife supported in a lateral projection on said base rod, a gage on said base rod located on each side of said knife, with means for adjustably securing said gages in different positions on said base rod, graduations on said base rod on one side of said knife, and an adjustable guide rod located in said gages and extending parallel with the base rod, substantially as and for the purpose specified.

30 4. In a cutter for flexible material, a base rod, a knife supported thereon, a gage located on said base rod on each side of said knife, means for adjusting the positions of the knife and gages relative to each other to correspond to the width of the material and to the width of cut, and a guide rod supported in said gages parallel with said base rod, substantially as specified.

40 In testimony whereof, I have hereunto set my hand this 29 day of January, 1907.

RICHARD T. MORE.
